UNITED STATES PATENT OFFICE

112,409

DESIGN FOR A PICTURE FRAME

Abraham Golden, Chicago, Ill.

Application October 4, 1938, Serial No. 80,247

Term of patent 3½ years

To all whom it may concern:

Be it known that I, Abraham Golden, a citizen of the United States, residing at Chicago, in the county of Cook and State of Illinois, have invented a new, original, and ornamental Design for Picture Frames, of which the following is a specification, reference being had to the accompanying drawing, forming part thereof, in which:

Fig. 1 is a perspective view of a picture frame showing my new design; and

Fig. 2 is a side elevation thereof.

The lining shown in the marginal portion of the picture frame indicates a colored coating applied to the rear surface of a transparent plate.

I claim:

The ornamental design for a picture frame, as shown and described.

ABRAHAM GOLDEN.
